UNITED STATES PATENT OFFICE.

CHARLES E. LARSON AND ERICK ROSENDAHL, OF MINNEAPOLIS, MINNESOTA.

DENTAL CASTING MACHINE.

Application filed May 7, 1924. Serial No. 711,620.

Our invention provides a simple and highly efficient casting machine adapted generally for casting bodies of metal into molds by pneumatic pressure, but more especially adapted for use in casting silver, gold and platinum in making dental castings, such as inlays, bridges, plates, crowns and the like. The casting machine is also exceedingly well adapted for use in casting rings and other articles of jewelry. The casting machine will be hereinafter particularly described as used for its primary purpose, to wit: for making dental castings.

The pattern for the dental casting is curved or otherwise formed in wax and is then mounted on a sprue pin and is thereby supported on a sprue former base. An investment ring is then placed on the sprue former base and the investment material is placed in the ring and around the wax pattern. The investment ring is thereafter inverted and, by the application of heat, the wax pattern is melted and caused to run out of the mold. The investment material is formed with a cavity affording a crucible, and the bottom of this is connected to the top of the mold by a small sprue.

Our improved casting machine is designed to take the investment ring, with the mold formed as described, and by pneumatic pressure, to press the molten metal in the crucible through the sprue and into the mold. The preferred form of the casting machine and a modification thereof are illustrated in the accompanying drawings, wherein like characters indicate like parts throughout the several views.

Referring to the drawings:

Fig. 1 is a front elevation showing the improved casting machine;

Fig. 2 is a fragmentary section taken approximately on the line 2—2 of Fig. 1, some parts being removed;

Fig. 3 is a view partly in side elevation but chiefly in vertical section on the line 3—3 of Fig. 1;

Fig. 4 is a view partly in side elevation and partly in section on the same line as Fig. 3, but with some parts broken away and with the investment table raised and

subject to the means for producing pneumatic pressure; and

Fig. 5 is a view corresponding to Fig. 4, but illustrating a modified construction.

Describing first the preferred construction illustrated in Figs. 1 to 4, inclusive, the numeral 6 indicates an upright tubular frame casting substantially closed at its top and provided with a forwardly projecting horizontal supporting bracket 7. An oven 8, shown as in the form of a rectangular casting, is rigidly secured to the lower portion of the tubular frame 6 and affords a portion of the frame base. This oven 8 is preferably provided with a separately formed oven bottom 9 and with a door 10. As shown, the bottom plate 9 is provided with a central air passage 11 and with small gas burner ducts 12 that lead from an annular gas supply channel 13, which latter will be connected to a suitable gas supply, not shown. At its upper portion, the oven 9 is shown as provided with a vent opening 14.

At its front, the frame 6 is formed with a flat surface 15 and, at the outer edges thereof, has rigidly secured parallel upright guide strips 16 that guide a flat plate 17 for vertical sliding movements. Secured to the vertically movable plate 17 and projecting horizontally forward therefrom is an investment table 18 that is under strain to move upward with the plate 17, this, as shown, being accomplished by a weight 19 located in the tubular frame 6 and connected to the vertically movable plate 17 by a cable 20 that runs over a guide sheave 21 journaled on the top of the frame 6.

The investment table is normally held downward and restrained against upward movement by a latch dog 22 slidably mounted in one of the guide strips 16, (see particularly Fig. 1). The beveled inner end of the latch dog 22 normally engages the upper edge of the vertically movable plate 17. For conveniently moving the latch dog 22 into a releasing position, there is provided a finger-actuated tripping lever 23 pivoted to a projection of one of the guide strips 16 and subject to a leaf spring 24, which latter normally holds the latch dog 100

22 in operative position. The table 18 is shown as provided with projecting arms 25 and 26, which may be conveniently engaged to press the investment table back to its normal retracted position shown in Figs. 1 and 3, where it will, of course, be held by the dog 22.

The projecting upper bracket 7 supports a depending cylinder 27 and forms the upper head of said cylinder. Working within said cylinder is a piston 28, which is preferably not only held normally downward by gravity but is also subject to a light coiled spring 29. The piston 28 has a depending axial tube 30, to the lower end of which is a sort of supplemental piston 31 is attached, as shown, by threaded engagement. By reference to Fig. 3, it will be noted that the lower end of the cylinder 27 has an inturned stop flange that limits the downward movement of the piston 28, and by reference to Fig. 4, it will be noted that the supplemental piston 31 is of such size that it will freely clear said flange when moved upward into the cylinder. Secured to the lower face of the supplemental piston 31 is a disc-like facing 32 of somewhat flexible material, preferably a felted fibrous sheet of asbestos. The supplemental piston 31 has a central recess 31' and the facing 32 has air discharge ports 32' that communicate with said recess.

An air tube 33 is secured to the head of the bracket 7, as shown, by a stuffing box 34, and at its outer end is shown as connected to a pressure gauge 35 and to a tubular valve casing 36, which latter, as shown, is screwed into a valve seat 37 formed in the head of the bracket 7 and connected to the interior of the cylinder through an air discharge port 38. The port 38 is yieldingly closed against the outflow of air from the cylinder by a pressure-producing valve 39 that is yieldingly closed by a spring 40. The tension of the spring 40 may be adjusted by a screw rod 41 that works with threaded engagement through the head of the valve casing 36 and presses a small follower 42 against said spring. At its outer end, the screw 41 is provided with a graduated head 43 that cooperates with a fixed pointer 44 on the upper end of the said valve casing. The head-forming portion of the bracket 7 is further provided with a vent port 45 that is normally closed by a petcock 46 that is preferably of the self-closing type.

As a simple means for preventing rebounding of the investment table 18 and the parts carried thereby, immediately following initial contact of the investment ring with the facing 32 of the supplemental piston 31, there is provided a spring-pressed retaining dog 47 shown as pivoted to the table 18 at 48 with its upper end working freely

through a slot in said table and subject to a releasing cam 49 on the inner end of a small rock shaft 50, which latter is journaled to flanges on the table 18 and is provided at its extended end with an offset finger piece 50'. The laterally extended lower end of the dog 47 is preferably serrated and toothed and extended below the sliding plate 17 and arranged for engagement with a serrated or fine-toothed bar 51 set into the flat front face of the tubular frame 6, in position to be engaged by said dog when the table 18 is in its uppermost positions.

The investment ring or flask is indicated by the letter A; the investment material contained in said ring is indicated by the letter B; the mold cavity of said investment material is indicated by the letter C; the crucible-forming depression is indicated by the letter D; the sprue passage connecting the crucible to the mold cavity is indicated by the letter E; and the gold or other material to be cast is indicated by the letter F. Here it may be noted that the investment table 18 is provided with a depressed seat that receives and quite closely fits the lower portion of the investment ring A and holds the same in axial alignment with the cylinder 27, main piston 28 and supplemental piston 31, so that when the investment table is moved upward, the upper edge of said investment ring will be forced against the pliable asbestos or similar facing 32.

Operation.

In the use of the casting machine described, the mold cavity, the crucible-forming cavity, and the sprue will be formed in the investment ring A, as already indicated. After the wax model has been mounted into the investment material contained in the investment ring, the sprue pin will be removed, the investment ring will be inverted and placed in the oven 8 and therein subjected to heat produced by gas flames from the burner passages 12 and the wax model 110 thereby fused and caused to run by gravity out of the mold. The fused wax will, by the conical upper surface of the bottom of the oven, be drained out through the axial passage 11. After this has been done, the investment ring will be again turned right side up and placed on the investment table 18 while the latter is in its lowered position, and then the gold or other metal F will be fused by a blow torch or the like. When the metal has been properly fused within the crucible D, it will, of course, spread out and entirely cover the sprue E, but will not, under the action of gravity, run into the mold. The investment table is then released by depressing the outer end of the trip lever 23, which retracts the retaining dog 22, and this allows the weight 19 to quickly raise

the investment table with the investment ring. When the upper edge of the investment ring A is pressed against the facing 32 of the supplemental piston 31, the pressure and continually acting force of the weight 19 will cause the main and supplemental pistons to move upward within the cylinder 27, thereby compressing the air contained in the latter. The air compressed within the cylinder finds its escape by raising the pressure-reducing valve 39 and passing through the casing 36 to the axial tube 33, sleeve 30, cavity 31' and passages 32', and into the crucible-forming cavity D, where it exerts its pressure on the upper surface of the molten metal F, and such pressure causes the molten metal to flow down through the sprue E and to quickly and completely fill the mold cavity C. Obviously, the force of the air pressure on the molten metal, and consequently the force with which the molten metal will be forced into the mold, will depend upon the adjustments of the pressure-reducing or choke-acting valve 39, and which action is regulated by adjustments of the screw 41, which, as shown, varies the tension of the spring 40. Obviously, the greater the tension of the spring 40 on the valve 39, the less will be the escape of air through the port 38 and, consequently, the less will be the pressure of the air on the molten metal. The pressure gauge 35 will serve to indicate the pressure under which the valve 39 operates to vary the escape of air and, consequently, the force of the air on the molten metal.

When the investment ring is quite violently thrown against the facing of the supplemental piston, as described, the air in the cylinder will be substantially compressed and will tend to react and produce a vibration or downward movement of the piston structure, and such downward movement would tend to produce a partial vacuum in the crucible D, which would tend to draw the molten metal more or less out of the mold. In the arrangement described, however, the retaining dog 47, by engagement with the rack 51, positively holds the table and investment ring to the highest position to which it may at any time be forced, and this, as is evident, obviates the partial vacuum with the resulting detrimental action.

When the table 18 is to be again lowered, it is only necessary to press on the offset finger piece 50' of the rock shaft 50, thereby causing the cam 49 to press the retaining dog 47 into releasing position, and then, by taking hold of the hand pieces 25 and 26, the table can be readily forced down to its normal position and there secured by the latch 22. In resetting the machine, the piston should be restored to normal position,

and this, the spring 41, assisted by gravity, will quickly accomplish when the petcock 46 is opened.

The construction illustrated in Fig. 5 is like that above described with the following exceptions, to wit: in this arrangement, the cylinder 27', which corresponds in most respects to the cylinder 27, is secured to the head-forming portion 7' of the bracket projected from the upper end of the tubular frame 6. In this arrangement, however, a piston proper is not placed within the cylinder, but in lieu thereof, the cylinder is provided in its upper portion with a hollow cylindrical water container 52 and below said container with an absorbent pad 53, preferably of felted fibrous asbestos. The bottom of the water container 50 is provided with a plurality of water drip perforations 54 that will deliver water onto the absorbent pad 53 and keep the same saturated with water. Water is adapted to be inserted into the container 52 through a passage 55 formed in the head 7' and in the top of the container 52, and this passage is adapted to be normally closed by a removable cap 56.

With this arrangement, when the hot flask and molten metal therein contained are forced against the water-soaked pad 53, steam will be generated and the steam will produce the pneumatic pressure required to force the molten metal down into the mold cavity.

The so-called investment ring A, of course, constitutes the flask for containing the investment or mold-forming material. In the construction illustrated in Figs. 1 to 4, inclusive, the supplemental piston head constitutes a flask-covering or closing plate, and in the construction illustrated in Fig. 5, the absorbent material 53 constitutes the flask cover or closing plate.

The pressure gauge shown in the drawings may be left permanently attached to the device, but after the needle valve has been properly regulated for different predetermined adjustments, the gauge may be removed and the pipe connection, from which it is taken, plugged.

A little experience with the device will teach the operator just the setting of the needle valve required to produce pressure for casting any particular device and, hence, it will be an easy matter to preset the valve for the predetermined desired pressure.

The striking plate or supplemental piston of the preferred form of the device is spaced from the main body of the piston and is connected thereto only by a small neck portion, which has but little heat-conducting capacity. This permits the air to circulate freely around or over the supplemental piston to reduce the temperature thereof during the casting action and prevent the main

piston from being materially expanded or contracted, either by heat radiation or conduction.

What we claim is:

- 6 1. In a casting machine, a supporting frame, a cylinder supported by the upper portion of said frame, a flask cover associated with said cylinder, a table located below said flask cover and arranged to carry a flask against the latter, yielding means tending to thus move said table upward, means for restraining said table against such movement and for releasing the same at will, and means whereby upon contact of the flask with said flask cover pressure will be produced in said flask to force molten metal into a mold cavity within said flask.
- 10 2. The structure defined in claim 1 in which the means for moving said table upward includes a weighted cable.
- 15 3. The structure defined in claim 1 in further combination with a retaining dog operative to hold the table with the flask in contact with said flask cover and against downward rebounding movement.
- 20 4. A casting machine comprising a hollow upright frame provided with an offset head-forming bracket, a cylinder secured to said head-forming bracket, a flask cover associated with said cylinder, a flask-supporting table movable vertically on said frame and arranged to position a flask against said flask cover when said table is moved upward, means for holding said table in a lowered position and for releasing the same, a guide sheave on the upper portion of said frame, a cable extended over said sheave and attached to said table, said sheave at its other end having an attached weight working within said hollow frame.
- 25 5. In a casting machine, the combination with a frame, of an upright cylinder supported in a laterally offset position by the upper portion of said frame, a normally depressed piston in said cylinder provided with a flask cover, a flask-supporting table movable vertically on said frame and arranged to support a flask and to carry the same against said flask cover, yielding means tending to move said table upward, means normally holding said table depressed and for releasing the same at will, and an air discharge conduit leading from said cylinder through said piston and flask cover and arranged to deliver air under compression to the flask when the latter is moved against said flask cover and said piston is caused to move upward in said cylinder.
- 30 6. In a casting machine, the combination with a frame, of an upright cylinder supported in a laterally offset position by the upper portion of said frame, a normally depressed piston in said cylinder provided with a flask cover, a flask-supporting table movable vertically on said frame and arranged to carry the same against said flask cover, yielding means tending to move said table upward, means normally holding said table depressed and for releasing the same at will, and an air discharge conduit leading from said cylinder through said piston and flask cover and arranged to deliver air under compression to the flask when the latter is moved against said flask cover and said piston is caused to move upward in said cylinder.
- 35 7. The structure defined in claim 5 in which there is a normally closed air-venting valve which when opened permits free downward movement of said piston.
- 40 8. The structure defined in claim 5 in which there is a normally closed air-venting valve which when opened permits free downward movement of said piston, and a spring tending to impart downward movement to said piston.
- 45 9. The structure defined in claim 5 in which there is a normally closed air-venting valve which when opened permits free downward movement of said piston, and a cylinder head, a cylinder secured to and depending from said cylinder head, a piston working in said cylinder and provided with a flask cover and a depending tubular stem, of an air pipe extended axially through said cylinder head and telescoped into the tubular stem of said piston head, an air conduit
- 50 10. In a casting machine, the combination with a suitable frame provided at its upper portion with an offset bracket forming a cylinder head, a cylinder secured to and depending from said cylinder head, a piston working in said cylinder and provided with a flask cover and a depending tubular stem, of an air pipe extended axially through said cylinder head and telescoped into the tubular stem of said piston head, an air conduit

movable vertically on said frame and arranged to support a flask and to carry the same against said flask cover, yielding means tending to move said table upward, means normally holding said table depressed and for releasing the same at will, and an air discharge conduit leading from said cylinder through said piston and flask cover and arranged to deliver air under compression to the flask when the latter is moved against said flask cover and said piston is caused to move upward in said cylinder, and in further combination with an adjustable pressure-producing valve in said air delivery conduit, the said flask cover being spaced from the piston proper and normally being below said cylinder but freely movable in said cylinder.

7. In a casting machine, the combination with a frame, of an upright cylinder supported in a laterally offset position by the upper portion of said frame, a normally depressed piston in said cylinder provided with a flask cover, a flask-supporting table movable vertically on said frame and arranged to support a flask and to carry the same against said flask cover, yielding means tending to move said table upward, means normally holding said table depressed and for releasing the same at will, and an air discharge conduit leading from said cylinder through said piston and flask cover and arranged to deliver air under compression to the flask when the latter is moved against said flask cover and said piston is caused to move upward in said cylinder, and in further combination with an adjustable pressure-producing valve in said air delivery conduit, the said flask cover being spaced from the piston proper and normally being below said cylinder but freely movable in said cylinder, said flask cover having a pliable facing with centrally located air passages therein.

8. The structure defined in claim 5 in which there is a normally closed air-venting valve which when opened permits free downward movement of said piston.

9. The structure defined in claim 5 in which there is a normally closed air-venting valve which when opened permits free downward movement of said piston, and a cylinder head, a cylinder secured to and depending from said cylinder head, a piston working in said cylinder and provided with a flask cover and a depending tubular stem, of an air pipe extended axially through said cylinder head and telescoped into the tubular stem of said piston head, an air conduit

10. In a casting machine, the combination with a suitable frame provided at its upper portion with an offset bracket forming a cylinder head, a cylinder secured to and depending from said cylinder head, a piston working in said cylinder and provided with a flask cover and a depending tubular stem, of an air pipe extended axially through said cylinder head and telescoped into the tubular stem of said piston head, an air conduit

including a valve casing connecting the upper portion of said air pipe to the interior of said cylinder, and an adjustable pressure-reducing valve in said valve casing.

5. 11. The structure defined in claim 10 in combination with a normally closed air-venting valve which when opened permits free flow of air into said cylinder and free downward movement of said piston.
- 10 12. The structure defined in claim 10 in

combination with a spring normally closing said pressure reducing valve, a spring tension adjusting device including a screw, a graduated head secured to said adjusting screw, and a relatively fixed cooperating pointer.

In testimony whereof we affix our signatures.

CHARLES E. LARSON.
ERICK ROSENDAHL.
